UNITED STATES PATENT OFFICE.

JOHN F. CORRIGAN, OF NEW BEDFORD, MASSACHUSETTS.

DESIGN FOR A BOTTLE.

SPECIFICATION forming part of Design No. 13,175, dated August 15, 1882.

Application filed July 7, 1882. Term of patent 7 years.

To all whom it may concern:

Be it known that I, JOHN F. CORRIGAN, a citizen of the United States of America, residing at New Bedford, in the county of Bristol and State of Massachusetts, have invented 5 certain new and useful Improvements in Designs for Bottles; and I do hereby declare the following to be a full, clear, and exact description of the invention, such as will enable others skilled in the art to which it appertains to 10 make and use the same, reference being had to the accompanying drawing, and to letters or figures of reference marked thereon, which forms a part of this specification.

15 My invention relates to an improvement in designs for bottles; and it consists in forming enlargements upon the upper and lower portions of the body, so as to produce a new and pleasing effect.

20 The accompanying drawing represents a side elevation of a bottle embodying my invention.

A represents the neck of the bottle, which has a flange formed upon its top, and which may be of any desired length. From the bot-

tom of the neck the upper portion of the body 25 swells abruptly either by straight lines or with a curve, so as to form an oblate bulb, upon which may be cut, engraved, or ornamented in any suitable manner oval figures or designs, like what are here shown, or figures of any kind 30 which will add to the beauty of the bottle. The central portion of the body is cylindrical, and upon it the word "Garfield" will be engraved, marked, or cut in any suitable manner. The lower portion of the body is enlarged, as shown, 35 and upon the upper portion of this enlarged part may be engraved any suitable designs or figures.

Having thus described my invention, I claim—

40 A design for a bottle, substantially as shown and described.

In testimony whereof I affix my signature in presence of two witnesses.

JOHN F. CORRIGAN.
